UNITED STATES PATENT OFFICE

99,913

DESIGN FOR A CLOSURE FOR A BOTTLE OR THE LIKE

Merrill M. Kistner, Indianapolis, Ind.

Application May 10, 1935, Serial No. 56,769

Term of patent 14 years

To all whom it may concern:

Be it known that I, Merrill M. Kistner, a citizen of the United States, residing at Indianapolis, in the county of Marion and State of Indiana, have invented a new, original, and ornamental Design for a Closure for a Bottle or the like, of which the following is a specification, reference being had to the accompanying drawing, forming part thereof.

Fig. 2 is a plan view of the closure shown in Fig. 1, but on a somewhat smaller scale.

I claim:

The ornamental design for a closure for a bottle or the like substantially as shown.

MERRILL M. KISTNER.
